ILLUMINATED SIGN CONSTRUCTION

Lindsley Schepmoes, New Haven, Conn., assignor
to The Safety Car Heating & Lighting Com-
pany, a corporation of New Jersey

Application September 19, 1931
Serial No. 563,756

21 Claims. (Cl. 40—133)

This invention relates to an illuminated sign construction.

One of the objects of this invention is to provide a simple, practical and thoroughly durable illuminated sign. Another object of this invention is to provide a device of the above character which will be attractive and striking in appearance while increasing the visibility thereof. Another object of this invention is to provide a device of the above character in which the individual indicia are successfully set off in a clear and distinct manner so that they may be readily legible. Another object of this invention is to provide a device of the above character which will be of ready and inexpensive manufacture.

Another object of this invention is to provide a device of the above character which will be efficient and reliable in operation. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings, in which are shown several of the various possible embodiments of my invention,

30 Figure 1 is a perspective view of an illuminated sign embodying certain features of my invention;

Figure 2 is a front elevation of the sign as shown in Figure 1, certain of the parts thereof being shown in detail;

Figure 3 is a horizontal cross-section taken along the line 3—3 of Figure 2;

Figure 4 is a horizontal cross-section of an illuminated sign such as that shown in Figure 1, embodying certain other features of my invention;

Figure 5 is a cross-section taken along the line 5—5 of Figure 4, and

Figure 6 is a fragmentary top plan view of a portion of the sign as shown in Figure 1.

Similar reference characters refer to similar parts throughout the several views of the drawings.

Referring now to the drawings in detail, there is shown in Figure 1 an illuminated sign generally indicated at 10. More specifically, sign 10 includes a frame 11 within which is mounted and connected thereto a mirror-member 12 in a manner to be described more fully hereinafter. Suitably positioned so as to extend from

the front surface of mirror-member 12 and thus be set off in relief therefrom are a series of indicia generally indicated at 13, these indicia being of any desired form. It should be understood that by the term "indicia" I mean any symbols, configurations, letters or other intelligible insignia tending to convey a certain impression, idea or thought.

Although I may employ any specular reflecting surface for mirror-member 12, I have found it very advantageous to form this member so that the front surface thereof, as viewed in Figure 1, is the reflecting surface. For this purpose I have found sheet metal plated with highly polished chrome to be very desirable and economical. The chrome surface or reflecting surface of such a piece of metal is upon the front surface of the metal, as viewed in Figure 1, one of the differences between such a mirror-member and an ordinary mirror being that the ordinary mirror, formed from a suitable transparent material such as glass, usually carries its reflecting surface upon the rear side thereof. Although it is possible to use such a mirror, I have found it highly advantageous and more practical to employ a mirror-member having a front reflecting surface.

Indicia 13 may be formed from certain translucent materials, the exact nature of which will be described more fully hereinafter. For purposes of illustration, I have here shown the indicia spelling the word "Exit" under which appears an arrow 14 of similar construction. Indicia 13, extending from mirror-member 12 to a plane or planes spaced from the plane surface thereof, as viewed in Figure 1, are preferably formed with walls 15 substantially at right angles to the plane surface of the mirror-member and have a front or a top portion 16 converging from walls 15 to form substantially convex tops therefor. Likewise, arrow 14 has walls 17 similar to walls 15 and a top side 18 similar to the tops 16. However, it should be understood that the indicia 13 may take any desired form, the present form being considered most desirable for an illuminated exit sign, such as is generally placed upon or above the fire exits in theatres, public halls, and the like.

Frame 11, to which mirror-member 12 is secured, preferably is shaped to have a rearwardly extending flange 19. Still referring to Figure 3, flange 19 extends about and is close fitted with a casing generally indicated at 20. Casing 20 may be of any suitable character adapted to rest within a cavity or recess in the wall or on a plane surface thereof. However, I have here shown

casing 20 mounted within a cavity 21 in a wall 22. To secure casing 20 within cavity 21, I provide screws generally indicated at 23 passing through the rear side of casing 20 and thence 5 into wall 22. The manner of attaching frame 11 to casing 20 is substantially similar to the construction used in the embodiment of my invention shown in Figures 4, 5 and 6 and will be described more fully hereinafter.

10 For purposes of convenience, any reference herein to a direction as "rearward" indicates a direction toward the top of the page when viewing Figure 3, and any direction signified as "forward" indicates a direction toward the bottom 15 of the page when viewing the above-mentioned figure.

Indicia 13 may be secured to mirror-member 12 in any convenient manner over openings generally indicated at 24, substantially following the 20 shape of such indicia. These indicia may be formed from any suitable material, although in certain instances it is more desirable to use a substance of a specific character for best results, as will be described more fully hereinafter. Thus, 25 indicia 13 may be formed from translucent glass or synthetic resins such as phenolic condensation products. The indicia so formed with walls 15 and tops 16 are substantially similar in dimensions and shape to opening 24, as described above, 30 and may be inserted therethrough. The opposite sides of indicia 13 are open, as best seen in Figure 3, and extending outwardly from walls 15 thereof and substantially at right angles thereto are flanges generally indicated at 25. The periphery of flanges 25 is larger than openings 24 and thus these flanges lie against the inner side 35 of mirror-member 12 to prevent any forward displacement of the indicia.

To secure indicia 13 to mirror-member 12 in 40 the position shown in Figure 1, I provide a series of soft metal clips 26 (Figure 3) secured to the rear side of mirror-member 12 and having free portions 27 extending toward openings 24 to overlap flanges 25. Thus, indicia 13 may be 45 inserted in openings 24 from the rear side of mirror-member 12, when portions 27 of clips 26 are in an upright position. When flanges 25 lie flush against the rear side of mirror-member 12, portions 27 of clips 26 are bent downwardly 50 upon the flanges to affix the indicia in their proper operative position.

In this instance, to provide suitable illumination for indicia 13, I prefer to use a glow-tube generally indicated at 28. Tube 28 may be of 55 the common glass construction containing a suitable gas as, for example, neon, which becomes illuminated when a current is passed therethrough. Thus, the opposite ends 29 and 30 (Figure 2) of tube 28 pass through a suitable insulator 31 slidably mounted in the rear side of casing 20. Conductors 32 and 33 are connected to suitable terminals on ends 29 and 30 of tube 28 thence to be led off from the wall and connected across a suitable source of high potential current. As 60 is more clearly shown in Figure 2, tube 28 extending from end 29 passes through substantially all portions of indicia 13 before returning to insulator 31 as end 30 and is held in this position by clips 28a secured to mirror-member 12. Accordingly, when tube 28 is lighted, all portions of indicia 13 are illuminated with substantially equal 65 intensity.

It will now be seen that when a suitable source of high potential current is connected to the terminals on the ends of tube 28 by conductors 32

and 33, light is emitted from tube 28 and consequently indicia 13 are illuminated. The color of the light emitted from tube 28 may be varied according to the character of the gas contained within the tube, and consequently the color of indicia 13 may likewise be varied in this manner. Furthermore, the color of the indicia may be varied by forming the indicia or tube 28 from substances having different colors. In order to increase the intensity of the light cast through indicia 13, I preferably provide a reflector 34 of any suitable shape and secured to the rear side of casing 20 as, for example, by rivets 35. Thus, light cast in a rearward direction from tube 28 is reflected by reflector 34 to be thrown in turn toward indicia 13.

Turning back to Figure 1, when tube 28 is emitting light as above described, thus to illuminate indicia 13, images A appear in mirror-member 12. These images are the complement or reverse of that portion of the indicia which is visible to the observer. They appear at the sides of the indicia, thus giving the impression that they are other portions of these indicia corresponding thereto in shape and size, the whole being suspended in a space. As described above, indicia 13 are set off in relief from the front surface of mirror-member 12. When illuminated, however, images A combine with the visible portions of indicia 13 (those portions set off in relief from mirror-member 12) to give the illusion to an observer that the letters are actually suspended in a space with no visible means of support and have twice as much bulk or mass as is actually the case. Furthermore, the light forming images A are in 105 turn reflected from the surface of mirror-member 12 instead of being absorbed thereby, to add to the intensity of the outline of the indicia. Accordingly, besides achieving an ornamental effect in an illuminated sign in this manner, I also 110 provide a sign whose indicia are so intensely illuminated as compared with the amount of light used for such illumination, that the visibility and legibility thereof is greatly and efficiently increased.

Turning now to Figure 4, I have shown another embodiment of my invention in which I prefer to use electrical incandescent lighting means. Thus, in this instance, I provide a casing generally indicated at 36 preferably set within a cavity 125 or recess 37 in a wall 38. Casing 36 may be secured to wall 38 within cavity 37 by screws 39 extending through the rear side of the casing and thence into the wall.

Suitably mounted upon the inner surface of the 130 rear side of casing 36 are a series of sockets 40, 41 and 42 of any convenient construction. Sockets 40, 41 and 42 are preferably connected in parallel by conductors 43 and 44 passing in turn through a suitable insulator 45. Bulbs 46, 47 and 48 are inserted in sockets 40, 41 and 42 respectively and, when conductors 43 and 44 are connected to a suitable source of current, these bulbs emit light. To add to the intensity of the light emitted from the bulbs, I preferably provide a 135 reflector 49 positioned to the rear of the bulbs and extending about the sockets. Reflector 49 may take any convenient shape, although I preferably form it concave in order to direct the greatest quantity of light rays toward indicia 13 (Figure 5). As is more clearly shown in Figure 5, reflector 49 is affixed to the rear side of casing 36 by a bracket 50 preferably soldered to the reflector and connected to the casing by rivets generally indicated at 51. When the bulbs are lighted in 140

- the above described manner, light is cast through indicia 13 and the intensity thereof is magnified by reflector 49. The color of this light may be varied according to the color of the bulbs used 5 and also the material from which indicia 13 is formed as described above. Upon the lighting of the bulbs, images A appear in mirror-member 12 to produce substantially the same effect as that described above with reference to Figure 1.
- 10 Although I may secure frame 11 to either casing 20 or casing 36 in any convenient manner, I prefer to provide in these casings, slots 52 in the top sides thereof, these slots being in substantial registry with lugs 53 extending downwardly from flange 19, as viewed in Figure 5, and substantially parallel to the plane of mirror-member 12. When frame 11 lies flush against the front edge of casing 20 or casing 36 (this construction being substantially identical in both 15 embodiments of my invention herein described) lugs 53 extend into slots 52 to hold the top portion of the frame firmly against the casing. Preferably, slots 52 are slightly larger than lug 53 so that the frame carrying mirror-member 12 may be swung in an upward direction, as viewed 20 in Figure 5, about slots 52 as an axis. At the bottom of frame 11, as viewed in Figure 5, I provide upon flange 19 a series of raised portions 54 extending toward casing 20 and in registry 25 with a series of indentations 55 upon the casing, when the bottom portion of the frame lies flush against the bottom edge of the casing.
- Thus, upon closing the frame on casing 20 or casing 36, raised portions 54 snap into indentations 55 to secure the frame against any front-wise displacement. However, if sufficient tension is exerted against the frame, it may be swung upwardly so that the various parts contained in casings 20 and 36 may be examined or repaired.
- 30 Furthermore, the parts mounted upon mirror-member 12 may also be repaired by removing the frame from the casing, this being accomplished by removing lugs 53 from slots 52, cords 32 and 33 (Figure 4) being of sufficient length to allow 35 the frame in this case to be moved forward sufficiently to obtain access to all of the parts within the casing and upon the rear side of the mirror-member.
- It will thus be seen that there is provided a 35 highly efficient and thoroughly practical device in which the several objects hereinbefore mentioned, as well as many others, are successfully achieved.
- As many possible embodiments may be made 50 of the above invention and as many changes might be made of the embodiment above set forth, it is to be understood that all matter hereinbefore set forth or shown in the accompanying drawings is to be interpreted as illustrative and 55 not in a limiting sense.
- I claim:
1. In an illuminated sign construction, in combination, a specular reflecting member, translucent indicia extending above said reflecting member, and means positioned behind the reflecting surface of said reflecting member for illuminating said indicia.
  2. In an illuminated sign construction, in combination, a reflecting member, translucent indicia extending above said reflecting member, means disposed behind said reflecting member for illuminating said indicia, and reflecting means positioned behind said illuminating means.
  3. In an illuminated sign construction, in combination, a reflecting member, translucent indicia positioned on said reflecting member and set off in relief therefrom, and glow-tubes positioned behind said indicia and adapted to illuminate said indicia.
  4. In an illuminated sign construction, in combination, a mirror, translucent letters extending through said mirror and positioned in relief from the reflecting surface of said mirror, and means for directing light through said letters.
  5. In an illuminated sign construction, in combination, means having a specular reflecting surface, a plurality of translucent indicia extending from said means and positioned in relief from and adjacent to said reflecting surface, and illuminating means positioned behind said reflecting surface.
  6. In an illuminated sign construction, in combination, a member having a specular reflecting surface, a translucent indicium extending from said reflecting surface, and glow-tubes positioned behind said reflecting member and adapted to direct light through said indicium.
  7. In an illuminated sign construction, in combination, a member having a specular reflecting surface, a translucent indicium extending from said reflecting surface, and electric illuminating members adapted to cast light through said indicium.
  8. In an illuminated sign construction, in combination, a member having a specular reflecting surface, a translucent indicium extending from said reflecting surface, electric illuminating means adapted to cast light through said indicium, and a reflector positioned behind said illuminating means.
  9. In an illuminated sign construction, in combination, a metallic member having a specular reflecting surface, translucent indicia extending above said reflecting surface and secured to said metallic member, and means for directing light through said indicia.
  10. In an illuminated sign construction, in combination, a sheet of metal, one surface of which is plated with a highly polished metal, a plurality of translucent indicia set off in relief from the plated side of said metal, and glow-tubes for directing light through said indicia.
  11. In an illuminated sign construction, in combination, a sheet of metal having a reflecting surface, a plurality of translucent letters set off in relief from said reflecting surface, and electric illuminating means adapted to throw light through said letters whereby complementary images of said letters appear in said reflecting surface.
  12. In an illuminated sign construction, in combination, a sheet of metal having a reflecting surface, a plurality of translucent letters set off in relief from said reflecting surface, glow-tubes adapted to throw light through said letters, and a reflector positioned behind said illuminating means.
  13. In an illuminated sign construction, in combination, a sheet of metal, one surface of which is plated with highly polished chrome, a plurality of translucent indicia extending through said sheet of metal and secured thereto, said indicia being positioned in relief from the plated surface of said metal, and electric illuminating means facing the unplated side of said metal and adapted to throw light through said indicia.
  14. In an illuminated sign construction, in combination, a sheet metal member having a specular reflecting surface, a series of translucent in-

- 5   dicia extending through said member and set off in relief from said surface, said indicia adjoining said surface, electric illuminating means positioned behind said member and adapted to throw light through said indicia, and a reflector positioned behind said illuminating means.
- 10   15. In an illuminated sign construction, in combination, a sheet metal member having a surface of highly polished chrome, a series of indicia extending through said member and above said surface thereof, the sides of said indicia substantially adjoining said surface, and an electric illuminating apparatus positioned behind said member and adapted to throw light through said indicia whereby complements of said indicia are reflected from said surface.
- 15   16. In an illuminated sign construction, in combination, a sheet metal member having a specular reflecting surface, a series of translucent indicia extending from said member and adjoining said reflecting surface, and illuminating means associated with said member and adapted to throw light through said indicia.
- 20   17. In an illuminated sign construction, in combination, a sheet metal member having a plated reflecting surface, a series of translucent indicia extending through said surface and adjoining said plated surface, and means adapted to cast light through said indicia.
- 25   18. In an illuminated sign construction, in combination, a sheet metal member having a reflecting surface, a series of indicia formed from translucent material extending through openings in said member and having flanges extending over the surface of said member opposite said reflecting surface, means extending over said flanges to hold said indicia in said position, and means adapted to cast light through said indicia whereby complementary images of said indicia are formed in said reflecting surface.
